CLAIM

The ornamental design for a double heart legs pillow, as shown and described.

DESCRIPTION

FIG. 1 is a front view of a double heart legs pillow showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front view thereof in its close position;

FIG. 9 is a rear view thereof in its close position;

FIG. 10 is a left side view thereof in its close position;

FIG. 11 is a right side view thereof in its close position;

FIG. 12 is a top plan view thereof in its close position;

FIG. 13 is a bottom plan view thereof in its close position; and,

FIG. 14 is a perspective view in its close position.

1 Claim, 7 Drawing Sheets
